SAMUEL SAMUELS, OF MOTT HAVEN, AND WALTER J. BRASSINGTON, OF BROOKLYN,
NEW YORK, ASSIGNEES TO THEMSELVES, WILLIAM PITTS, AND W. B. BURTNETT.

Letters Patent No. 65,951, dated June 18, 1867.

IMPROVEMENT IN LOCOMOTIVE ENGINES.

The Schedule referred to in these Letters Patent and making part of the same.

TO ALL WHOM IT MAY CONCERN:

Be it known that we, SAMUEL SAMUELS, of Mott Haven, in the county of Westchester, and State of New York, and WALTER P. BRASSINGTON, of Brooklyn, in the county of Kings, and State of New York, have invented a certain new and useful improvement for Supplying Locomotive Tenders with Water, of which the following is a full, clear, and exact description, reference being had to the accompanying drawing, forming part of this specification, and which represents a side elevation of a locomotive and tender with our improvement applied thereto, details employed in which are partly shown in section.

The object of our invention is the supplying of locomotive tanks or tenders with water, by means of a vacuum produced in such tanks, whereby, on the attachment of a hose or pipe establishing a connection of the same with an outside reservoir, at a considerably lower level it may be than the track, the water is, by the natural pressure of the external atmosphere, forced into the tank to supply it.

The nature of our invention consists in establishing the vacuum in the tank C, by the mechanical agency of a pump, worked by the locomotive engine, and in the arrangement of parts of the feed-pump with reference to the boiler, engine, and tender, whereby to exhaust the air from the tank, and in the arrangement of the air pipe relatively to the water-valve, for exhausting air from the tank of the tender. These devices for supplying locomotive tenders with water essentially differ from those plans which employ the direct agency of steam for the purpose, whether using the pressure of the steam on the surface of the water in the reservoir, or condensing it in the tank to elevate or feed the water by reason of a vacuum, though the mechanical agency we employ may, if desired, be used in connection with the latter.

Referring to the accompanying drawing, A represents the feed-pump of and as applied to a locomotive engine, and the location of which may be varied. B is the water-supply pipe to said pump, that is provided with valves *a b c*, and the supply pipe furnished with a cock, *d*, which latter is used to shut off or establish communication with the tender C, or water-tank thereof, near its bottom. D is an air pipe connecting the water-supply pipe B with the upper portion of the tank. This connection I prefer to establish in front of the cock *d*, and connect or control the cock *c* by a rod or handle, *e*, from the platform of the engine or its tender. Though capable of various modifications, as, for instance, in the disposition of the pump, several pipes and valves, or in the employment of a separate pump for exhausting from the tank to that which is used for pumping water into the boiler, the arrangement of parts represented in the accompanying drawing, while possessing advantages peculiar or incidental to it, but which are not of necessity requisite, will serve to illustrate the peculiar character or principle of our invention, which distinguishes it from others, and the operation of which is as follows:

When it is desired to exhaust the air from the tank of the tender C, the cock *d* is shut and the cock *c* is opened by means of the handle or rod *e*. This stops the action of the pump as regards its feeding water from the tank, and restricts it to exhaustion of air by the pipe D, which air forced along the water-supply pipe B, is expelled through the cock *c* into the outside atmosphere, say by a discharge nozzle, *f*. On the other hand, when it is desired to stop exhausting air, and confine the pump A to forcing water from the tank into the boiler of the engine, the cock *c* is shut, and the cock *d* is opened, when the valve *b* will be brought into play, in conjunction with the valve *a*, to force the water as required. Of course the action of the pump may be stopped or put on at pleasure for either purpose. To cause water to flow from an outside reservoir or pool by pressure of the external atmosphere into the vacuum in the tank, it will only be necessary to insert the outer end of a pipe or hose attached to a nozzle under control of a valve, arranged at any suitable position in the upper portion of the tank, say at a point indicated by red lines in the drawing. By using the same pump for both exhausting the air from the tank, and forcing the water into the boiler, there is a simplicity of arrangement as compared to the employment of separate pumps; also a similar advantage in connecting the air pipe D in front of the cock *d*, with the supply pipe B, that serves to supply water to the pump.

What is here claimed as new and useful, and sought to be secured by Letters Patent, is—

1. The combination, with the tank of a locomotive engine tender, of an air-pump so arranged as to admit of being worked by the engine, for the production of a vacuum in said tank, substantially as herein set forth.

2. The combination, with a locomotive engine and its tender, of a pump so arranged as to serve either purpose at pleasure, of exhausting air from the tank to facilitate supply of water to the latter, or of forcing water from the tank into the boiler, substantially as herein set forth.
3. In combination with the water-supply pipe B, and its stop-cock d, the air pipe D connected with the pipe B, in front of the said cock d, essentially as shown and described.

SAMUEL SAMUELS,
WALTER J. BRASSINGTON.
